(57) **CLAIM**

The ornamental design for a device to enable drinking from a can, as shown and described.

DESCRIPTION

FIG. 1 is a perspective view of a device to enable drinking from a can showing my new design;

FIG. 2 is a side view of the upper piece shown in FIG. 1 with the lower piece removed for ease of illustration;

FIG. 3 is a side view of the lower piece shown in FIG. 1 with the upper piece removed for ease of illustration;

FIG. 4 is a bottom view of the piece shown in FIG. 2;

FIG. 5 is a bottom view of the piece shown in FIG. 3;

FIG. 6 is a front view of the piece shown in FIG. 2;

FIG. 7 is a front view of the piece shown in FIG. 3;

FIG. 8 is a rear view of the piece shown in FIG. 2;

FIG. 9 is a rear view of the piece shown in FIG. 3;

FIG. 10 is a top plan view of the piece shown in FIG. 2; and,

FIG. 11 is a top plan view of the piece shown in FIG. 3.
